UNITED STATES PATENT OFFICE.

HENRY B. OATLEY, OF FLUSHING, AND WILLIAM E. WOODARD, OF FOREST HILLS, NEW YORK; SAID OATLEY ASSIGNOR OF ALL HIS RIGHT TO THE SUPERHEATER COMPANY, OF NEW YORK, N. Y.

LOCOMOTIVE.

Application filed June 16, 1922. Serial No. 568,823.

To all whom it may concern:

Be it known that we, HENRY B. OATLEY, citizen of the United States, and resident of Flushing, Long Island, New York, and **5** WILLIAM E. WOODARD, a citizen of the United States, and resident of Forest Hills, Long Island, New York, have invented certain new and useful Improvements in Locomotives, of which the following is a specification.

10 Our invention relates to boilers and concerns itself particularly with the combination of boilers with steam separators, the separator being either located in a steam dome or in a steam drum, or being otherwise similarly intimately associated with the boiler. It has for its object an improved arrangement whereby the water separated out from the steam may be readily disposed **15** of without the use of drips, check valves, etc.

The invention is illustrated in the accompanying drawing wherein Fig. 1 shows a portion of a boiler of this type in longitudinal central section with our invention installed; Fig. 2 being a section on line 2—2 of Fig. 1 looking in the direction indicated by the arrows.

The boiler shown by way of illustration **20** is a locomotive boiler of an ordinary construction, and includes the barrel 1 extending forward from the fire box. The fire box is limited in the usual way at the front by a tube sheet 2, at the rear by the back sheet 3, and at the top by the crown sheet 4. Extending in the usual way through the fire box is a series of arch tubes, only one of **25** which is shown, 5. This connects the front water space 6 with the back water space 7. The greatest proportion of steam in boilers of this type is generated immediately above **30** the crown sheet and in close proximity to the tube sheet 2. All of the steam is collected in the dome 8 whence it is conducted forward to the steam chests by means of the dry pipe 9.

For a number of reasons the steam dome itself presents an attractive location for a steam separator, which separates out water **35** carried along by the steam in its flow toward the entrance of the dry pipe 9. No matter what type of separator is used for this purpose, some means must be devised for getting rid of the water collected. The

entrance to the dry pipe 9 is at best only a **55** very small distance above the water level of the boiler and in the modern large types of locomotives this elevation is reduced to an extremely small amount. When the main throttle to the engine is open the pressure at **60** the entrance of the dry pipe 9 falls below that prevailing in the body of the boiler, this difference amounting in some cases to possibly several pounds. If the pipe intended to carry away the water collected in the separator opens directly into the body of the boiler water, the water will back up in this pipe due to the pressure difference spoken of, and flood the separator and be carried **65** into the dry pipe. To place a non-return **70** check valve into the pipe mentioned, which opens to allow water to drain out of the separator but does not permit the backward flow referred to, it will be found that within a short time the check valve becomes inoperative or at least partly so, due to **75** encrustation or collection of sediment or other causes.

Our invention is intended to provide for the removal of the water from the separator **80** by the novel and efficient means described below.

In dome 8 we located a separator which may be of any desired and appropriate type but which we show by way of illustration to be made up of the annular sheet 10, the lower conical plate 11 which is connected to the dry pipe as shown, and a second annular sheet 12 between the first one and the dry pipe and secured to the top of the steam dome as at 13. This second annular sheet preferably has at its lower end an upwardly turned flange 14 forming a trough 15. To enter the inlet of the dry pipe 9 steam must pass over the upper edge of sheet 10, downward between the two sheets 10 and 12, around the lower end of sheet 12, upward between this sheet and the dry pipe and so into the dry pipe. In its passage as just described it impinges against the sheets and dry pipe and particles of water will collect on them and be gathered in the trough 15 and in the space 16, whence it will be drained by the two pipes 17 and 18. These two pipes unite into the single pipe 19. Instead of providing this pipe 19 with a check valve and letting it open directly into the body of the boiler water, we lead this

pipe 19 to a point in the boiler, where there is a rapid circulation or movement of water and where an ejector-like or entraining effect may be obtained. By way of illustration the point selected is at the entrance of one of the arch tubes 5, the circulation of water through these arch tubes being very rapid. For convenience we show the pipe 19 carried out through the wall of the boiler at point 20 and brought around the side to the plug 21 into which it is screwed. A separate length 22 is screwed into this same plug so that in effect 22 forms a prolongation of 19. The length 22 is extended a short distance into the arch tube 5. It will be understood that the particular way in which we extend the pipe 19 so that its end reaches the desired point is to be taken only by way of illustration. As above stated, the point selected for ending pipe 19 is also only illustrative. It is sufficient to come within the spirit of our invention if this end is placed at any point where there is rapid circulation.

The purpose of placing the end of pipe 19 as described is to produce an induced flow from this pipe by means of the water surrounding it. In the form illustrated, for example, the water entering the arch tube 5 will induce a flow from pipe 19 and thus drain the trough 15 and space 16 and prevent any back flow of water to these points.

While we have described the invention in connection with a locomotive boiler, it will

be obvious that its use is not in any way restricted to boilers of this type. It is on the contrary, applicable to and of use in connection with almost any type of boiler. Wherever the separator is, on account of limitation in headroom or for some other reason, located at only a slight elevation above the boiler water level and there is some point in the boiler where the water is circulating with relatively high velocity, our invention will be found applicable.

What we claim is:

1. In a boiler of the locomotive type, the combination of a steam dome; a separator in the dome; a rear water leg; a front water leg; a circulating tube connecting a high point of the former with a low point of the latter and extending through the firebox; and a pipe leading from the water collecting space of the separator through the outer sheet of the front water leg and a short distance into the circulating tube; said pipe being spaced from the walls of the circulating tube.

2. In a boiler of the locomotive type, the combination of a separator in direct communication with the steam space; two water legs; a circulating tube connecting the two water legs and extending through the firebox; and a pipe leading from the water-collecting space of the separator and extending into the inlet end of the circulating tube.

HENRY B. OATLEY.
W. E. WOODARD.
